UNITED STATES PATENT OFFICE

MATTHEW J. FALK, OF MILWAUKEE, WISCONSIN, ASSIGNOR TO BUFA LABORATORIES, OF MILWAUKEE, WISCONSIN, A CORPORATION

DESIGN FOR A TOOTHBRUSH

Application filed September 6, 1932. Serial No. 44,762. Term of patent 14 years.

To all whom it may concern:

Be it known that I, MATTHEW J. FALK, a citizen of the United States, and a resident of Milwaukee, in the county of Milwaukee, and State of Wisconsin, have invented a new, original, and ornamental Design for a Toothbrush, of which the following is a specification, reference being had to the accompanying drawing, forming part thereof.

I claim:

The ornamental design for a toothbrush, as shown.

In testimony that I claim the foregoing I have hereunto set my hand at Milwaukee, in the county of Milwaukee and State of Wisconsin.

MATTHEW J. FALK.
